Be it known that I, HORACE G. As shown in the drawings, the leading or material features of my design consist of a ¹⁵ pedestal or base 5, in configuration a truncated pyramid, a cabinet 6, surmounting the base 5, the same being polygonal in form in

cross-section, two circular disks 8 and 9, interposed between the cabinet 6 and the base 5, and the radially-mounted frames 10, ²⁰ mounting the cabinet 6.

Having described my invention, what I claim as new, and desire to secure by Letters Patent, is—

The design for a dispensing-cabinet, as ²⁵ herein shown and described.

In testimony whereof I have signed my name to this specification in the presence of two subscribing witnesses.

HORACE G. STRIPE.
